SPARK PLUG

Alessandro Tebaldi, Milan, Italy

Application April 27, 1932, Serial No. 607,822,
and in Germany August 11, 1931

12 Claims. (Cl. 123—169)

This invention relates to improvements in spark plugs for internal combustion engines.

As known, it is difficult to obtain a spark plug for internal combustion engines, particularly for aircraft engines working under high compression pressure, able to properly operate both at low and high engine speeds; in effect in operation the cooling characteristics of the known types of spark plugs, including those provided with heat dissipating means, are substantially invariable and therefore they cannot equally comply with thermal conditions prevailing in low speed and with those prevailing in full speed operation of the engine.

15 The object of the present invention is to provide a spark plug able to meet such requirement.

In accordance with the present invention a spark plug for internal combustion engines is provided which comprises an auxiliary heat sensitive and conducting member which is adapted to establish or suppress, according to the temperature it is subjected to due to conditions of operation of the engine, a supplemental thermal connection between the plug heat dissipating means and the parts of the same which are heated because of the engine operation in such a manner as the plug automatically maintains a substantially constant temperature throughout the full working range of the engine.

30 Embodiments of the present invention are hereinafter described by way of example with reference to accompanying drawing in which:

Figure 1 is a longitudinal central section of a construction of a plug according with this invention;

Figure 2 is a central longitudinal section of another embodiment of a spark plug;

Figure 3 is an end view of a separate member of the plug as hereinafter described;

40 Figure 4 is a longitudinal central section through a further embodiment of said plug.

In the embodiment of Figure 1, the plug comprises a screwthreaded hollow body 1 adapted to be screwed, as usual, into the wall of an engine cylinder. A hollow central electrode 8 is mounted in body 1 by means of a nut 2 screwed in said body 1 and intermediate insulating parts 4 and 5; a connecting and heat dissipating head 11 is fastened on the top of electrode 8 by means of a cap 7 screwed on electrode 8 and an insulating member 6 is located intermediate nut 2 and head 11. Electrode 8 provides a sparking point 9 which is adjacent to and cooperates with a sparking point 10 extending inwardly from the wall of hollow body 1.

Within the hollow electrode 8 a rod 13 is fastened by its end 14 screwed in the electrode point 9 and an ample gap is left intermediate facing outer and inner surfaces of rod 13 and electrode 8. The end of said rod 13 opposed to its connecting end 14 is in front of cap 7 and a gap 15 is provided intermediate the top face 13' of said rod and opposite bottom face 7' of cap 7.

Assuming the respective lengths and sizes of parts 8 and 13 and the materials of which each 65 of them is made are suitably chosen, when the temperature of the plug is below a predetermined value the top face 13' of rod 13 remains spaced from opposite face 7' of cap 7 and then no heat transference may arise from rod 13 to cap 7 and 70 heat dissipating head 11, the heat transference from heated portion 9 of electrode to said heat dissipating head taking place solely through body of electrode 8; on the contrary, when electrode 9, 8 is more strongly heated rod 13 expands and 75 its top face 13' engages opposite face 7' of cap 7, heat being thus conveyed to dissipating head 11 through the electrode body 8 and rod 13.

The described plug therefore provides two different conditions for heat dissipation and plug 80 cooling in respect of different running conditions of the engine, and thus the temperature and operation of the plug are maintained satisfactorily uniform throughout the full running range of the engine.

85 Figures 2 and 3 show a similar condition in which rod 13 is prevented from exerting a longitudinal thrust on plug parts 7 and 11 which could seriously affect the mounting and interconnection of the parts of the spark plug.

In this construction cap 7 provides a tapering downwardly projecting part 16 in its internal face opposite the top face of rod 13, and said rod 13 has at its free end a tapering recess 17 and transverse slots 18 providing resilient teeth 19; the 95 other parts of the plug are the same as described in connection with Figure 1.

On rod 13 extending under heat action, teeth 19 of rod engage tapering portion 16 of the cap 7 and thus they magnify the heat transmission from 100 electrode 8 to heat dissipating head 11, without an axial thrust being operative on projection 16, cap 7 and head 11, because said teeth are caused to resiliently bend outwardly at the time they are engaging tapering projection 16.

105 In both constructions of Figure 1 and of Figure 2 the respective or differential elongations of electrode 8 and rod 13 may depend upon the fact that they take up different temperatures because electrode 8 is subject to a large heat dissipation 110

towards external air while rod 13 is entirely protected against heat radiation; therefore parts 8 and 13 may be made of the same metal.

However said parts 8 and 13 may be made of materials having different thermal extensions in order to magnify their differential elongations.

Figure 4 shows a further embodiment in which a bimetallic member is used to provide the rod having one end secured on electrode 8, said bimetallic member consisting of two strips 13a, 13b made of metals having different coefficients of thermal extension or elongation and located adjacent to each other with their contacting faces soldered on each other at 13''. Said member 13a, 15 13b provides an inclined face 13' located opposite a face 20 of a metal member 21 fastened within cap 7 by having a flange 21' engaged between the end of hollow electrode 8 and the bottom face 7' of cap 7. On the plug being moderately heated 20 the parts of the same are in conditions of Figure 4, where a gap 15 exists intermediate faces 13' and 20 and therefore heat is conveyed only through electrode 8, but when plug is highly heated said member 13a, 13b bends owing to known operation 25 of such bimetallic units and its face 13' contacts with face 20 of member 21 thus securing a supplemental path for heat dissipation while no heavy longitudinal action is exerted against members 20, 7 and 11 because of the slope of contact 30 faces 13' and 20 of unit 13a, 13b and member 21 respectively.

What I claim as my invention and desire to secure by United States Letters Patent is:—

1. A spark plug for internal combustion engines comprising a plug body, an electrode fastened in and insulated from said body, heat dissipating means connected with said electrode, a heat sensitive member connected with said electrode and extending toward said heat dissipating 35 means and cooperating contact means on said heat dissipating means and member for resilient engagement of the same with each other, said contact means being spaced when said electrode and member are under a given temperature and 40 being carried into contact by said heat sensitive member due to its modification under effect of heat when the temperature of said electrode and member is above a given value.

2. A spark plug for internal combustion engines comprising a plug body, an electrode fastened in and insulated from said body, heat dissipating means connected with said electrode, a heat sensitive member connected with said electrode and extending toward said heat dissipating 50 means and cooperating contact means on said heat dissipating means and member for resilient engagement of the same with each other, said contact means comprising a split member and a tapering member engaging into said split member, and said contact means being spaced when said electrode and member are under a given temperature and being carried into engagement by said heat sensitive member due to its modification under effect of heat when the temperature 55 of said electrode and member is above a given value.

3. A spark plug for internal combustion engines comprising a plug body, a hollow electrode fastened in and insulated from said body, heat dissipating means connected with said electrode, a heat sensitive member loosely located within said electrode and connected with its sparking point and extending towards said heat dissipating means, and cooperating contact means on 70 75 said heat dissipating means and member for re-

silient engagement of the same with each other, said contact means comprising a split member and a tapering member engaging into said split member, and said contact means being spaced when said electrode and member are under a given temperature and being carried into engagement by said heat sensitive member due to its modification under effect of heat when the temperature of said electrode and member is above a given value.

4. A spark plug for internal combustion engines, comprising a plug body, an electrode fastened in and insulated from said body, heat dissipating means, and a heat sensitive member connected with said electrode and extending toward said heat dissipating means, said heat dissipating means and heat sensitive member having cooperating contact faces, said contact faces being spaced from each other when said heat sensitive member is heated at a given temperature during the operation of the plug and coming into contact with each other due to the modification of said heat sensitive member when said heat sensitive member is heated to a temperature above said first temperature.

5. A spark plug for internal combustion engines, comprising a plug body, an electrode fastened in and insulated from said body, heat dissipating means connected with said electrode, and a heat sensitive member connected with said electrode and extending toward said heat dissipating means, said heat dissipating means and heat sensitive member having cooperating contact faces, said contact faces being spaced from each other when said heat sensitive member is heated at a given temperature during the operation of the plug and coming into contact with each other due to the modification of said heat sensitive member when said heat sensitive member is heated to a temperature above said first temperature.

6. A spark plug for internal combustion engines, comprising a plug body, an electrode fastened in and insulated from said body, heat dissipating means, a bimetallic unit connected with said electrode and extending towards said heat dissipating means, said heat dissipating means and unit having cooperating contact faces, said contact faces being spaced from each other when said unit is heated at a given temperature during the operation of the plug and coming into contact with each other on said unit having its configuration altered under the effect of heat when said unit is heated to a temperature above said temperature.

7. A spark plug for internal combustion engines, comprising a plug body, an electrode fastened in and insulated from said body, heat dissipating means, a bimetallic unit connected with said electrode and extending towards said heat dissipating means, said heat dissipating means and unit having cooperating sloping contact faces, said sloping contact faces being spaced from each other when said unit is heated at a given temperature during the operation of the plug and coming into contact with each other on said unit having its configuration altered under the effect of heat when said unit is heated to a temperature above said first temperature.

8. A spark plug for internal combustion engines, comprising a plug body, a hollow electrode fastened in and insulated from said body, heat dissipating means, and a heat sensitive member loosely located within said electrode and connected with its sparking point and extending to-

ward said heat dissipating means, said heat dissipating means and heat sensitive member having cooperating contact faces, said contact faces being spaced from each other when said heat sensitive member is heated to a given temperature during the operation of the plug and coming into contact with each other due to the modification of said heat sensitive member when said heat sensitive member is heated to another temperature above said first temperature.

9. A spark plug for internal combustion engines, comprising a plug body, a hollow electrode fastened in and insulated from said body, heat dissipating means connected with said electrode, and a heat sensitive member loosely located within said electrode and connected with its sparking point and extending toward said heat dissipating means, said heat dissipating means and heat sensitive member having cooperating contact faces, said contact faces being spaced from each other when said heat sensitive member is heated at a given temperature during the operation of the plug and coming into contact with each other due to the modification of said heat sensitive member when said heat sensitive member is heated to another temperature above said first temperature.

10. A spark plug for internal combustion engines, comprising a plug body, a hollow electrode fastened in and insulated from said body, heat dissipating means, a heat sensitive member loosely located within said electrode and connected with its sparking point and extending toward said heat dissipating means, and cooperating contact means on said heat dissipating means and heat sensitive member for resilient engagement of the same with each other, said contact means being spaced from each other when said heat sensitive member is heated at

a given temperature during the operation of the plug and coming into contact with each other due to the modification of said heat sensitive member when said heat sensitive member is heated to another temperature above said first temperature.

11. A spark plug for internal combustion engines, comprising a plug body, a hollow electrode fastened in and insulated from said body, heat dissipating means, and a bimetallic unit loosely located within said electrode and connected with its sparking point and extending towards said heat dissipating means, said unit and heat dissipating means providing cooperating contact faces, said contact faces being spaced from each other when said heat sensitive member is heated at a given temperature during the operation of the plug and coming into contact with each other due to the modification of said heat sensitive member when said heat sensitive member is heated to another temperature above said first temperature.

12. A spark plug for internal combustion engines, comprising a plug body, a hollow electrode fastened in and insulated from said body, heat dissipating means, and a bimetallic unit loosely located within said electrode and connected with its sparking point and extending towards said heat dissipating means, said unit and heat dissipating means providing sloping faces for contact with each other, said sloping contact faces being spaced from each other when said heat sensitive member is heated at a given temperature during the operation of the plug and coming into contact with each other due to the modification of said heat sensitive member when said heat sensitive member is heated to another temperature above said first temperature.
